(57) **CLAIM**

I claim the ornamental design for a food container assembly, as shown and described.

DESCRIPTION

FIG. 1 is a top plan view of a food container assembly showing my new design;

FIG. 2 is a bottom plan view thereof;

FIG. 3 is a reduced top plan view thereof;

FIG. 4 is an enlarged exploded sectional view thereof taken along lines A-A of FIG. 3;

FIG. 5 is a side view of the food container shown in FIG. 1;

FIG. 6 is a side view of a component thereof;

FIG. 7 is a perspective view thereof; and,

FIG. 8 is an exploded view thereof.

1 Claim, 5 Drawing Sheets
